UNITED STATES PATENT OFFICE.

HERMAN GARRISON, OF CHICAGO, ILLINOIS.

CAN OPENER.

Application filed April 6, 1927. Serial No. 181,361.

The object of this invention is, to effect certain modifications in that can opener which is in practically universal use, and which operates as a lever of the second class, having a stock modified at the end so as to ride the rim of a can and afford a fulcrum thereon, and a downwardly offset uppercut knife which extends far enough past the end of the stock to permit penetration of the can by its point. The improvements sought are designed to facilitate the use of a longer knife than is made at the present time, and the specific object of this invention is to make certain changes in the terminal part of the knife which will contribute toward that result.

Fig. 1 is a side view, showing knife B riveted to stock A, which is set into a handle. The cutting edges above and below are indicated by double lines, the lower being required for the introduction of the longer knife into the can.

Fig. 2 is an incomplete top plan view, showing the lateral curvature of the knife, and the strip metal stock bent aside to form the fulcrum member D.

Fig. 3 is also an incomplete top plan view, showing the first step in the modification of the terminal part of the knife.

Fig. 4 is a front view of the fulcrum member D, showing the notch E which forms the fulcrum.

Fig. 5 will be referred to in explaining the relations between the curvature of the knife and the curvature of the can.

Fig. 6 shows the line of the incision made by the opener of Fig. 2.

The knife must be curved to fit circular cans. Our first problem is to determine the curvature best adapted to cans of varying sizes.

It is impossible to use on a large can a lengthened knife whose curvature is adapted to that of a small can. This statement needs no further proof than a glance at Fig. 5, which shows in full line a part of the circumference of a can $4\frac{1}{2}$ inches in diameter, and in dotted lines the kerfs cut by a knife whose curvature is set to a diameter of 3 inches. If, however, we give the knife the curvature of a large can, it is possible to adapt its operation to a small can.

We have a mutual relation among three eccentric curves: the curvature of the can, the lateral curvature of the knife, and the

re-entrant curve of the upper cutting edge, exhibited at G, Fig. 1.

By operating the instrument on a bias, we can make the incision conform to the curvature of the smaller can, provided we can bring the upper cutting edge into intimate contact with the rim of the can. The chief obstacle met with is due to the fact that, in order to introduce a lengthened knife into the can, it is of great advantage to increase the length of that part of the knife which lies beyond the end of the stock, shown at P, Figs. 1, 2 and 3. This must be of considerably greater length than in the ordinary can openers of this type.

This part of the knife, when applied to small cans, is very much in the way, and even though it be made of spring steel, it is likely to pierce the wall of the can instead of moving along on the inside. The most obvious device for meeting the difficulty is to bend the part P to one side, as shown in Fig. 3. This, however, will add to the difficulty of insertion, it being apparent that penetration can be more easily effected when the point is more nearly in line with the direction of the stock.

To give the desired direction to the point, I employ the reverse curve shown in Fig. 2, beginning at K. The shoulder formed by an increase of curvature in the knife will impede its introduction into the can, if we adopt the usual method of pushing the point forward and downward. We therefore adopt a different method. When the knife has penetrated the surface and its downward movement is checked by the fulcrum member, we move the handle backward and pry the lower cutting edge into the can, the elongated upper margin at P acting as a fulcrum. The efficiency of this fulcrum will be increased by blunting the upper edge of the part P, as shown in Fig. 1.

In Fig. 6 the full line represents in part the rim of a can $3\frac{1}{4}$ inches in diameter, and the dotted line indicates the path of the incision, the direction of the advancing knife being shown by the arrow. The line MS corresponds to the initial incision formed by inserting the point of the knife at M and prying the knife into the can. The line NV shows the next kerf. It will be seen that by this device I have effectually disposed of the obstacle presented by the projecting part of the knife. The blunt marginal portion ad-

adjacent the point of the knife is an ancient and well known structure employed on those openers which operate as levers of the first class in order to prevent dislodgment of the point at the completion of a kerf. It may be observed that in this instrument the structure referred to serves an entirely different purpose, and is functionally related both to the lower cutting edge with which it co-operates, and to the shoulder formed by the change in curvature of the knife, which necessitates the use of the upper margin as a fulcrum.

I claim:

18 1. A can opener in the form of a lever of the second class, having a guiding fulcrum formed by a recess at the end of a handled stock, and a downwardly offset uppercut knife, laterally curved in the direction of its length and extending forward past the guiding fulcrum; said knife being provided with an additional cutting edge on its lower margin and having its upper cutting edge rearwardly concave in outline; and that part of said knife which lies farther forward than the guiding fulcrum being laterally offset

by a reverse curve, the direction of displacement of the offset portion being toward that side of the instrument on which is situated the center of curvature of the directional curve of the knife.

2. A can opener in the form of a lever of the second class, having a guiding fulcrum formed by a recess at the end of a handled stock, and a downwardly offset upper-cut knife secured to the stock and extending forward past the guiding fulcrum; said knife being laterally curved in the direction of its length and provided with an additional cutting edge on its lower margin; that portion of said knife which projects past the end of the fulcrum-bearing stock being laterally offset by a curved jog, the direction of displacement of the offset portion being toward the inner side of the directional curve of the knife; and the pointed end of the instrument being provided with a flat upper face having a width of as great a magnitude as the thickness of the body of the knife.

HERMAN GARRISON.
